[57] CLAIM

The ornamental design for a brush dispenser for shoe polish or other liquids, as shown and described.

DESCRIPTION

FIG. 1 is a perspective view of a brush dispenser for shoe polish or other liquids, showing our new design;

FIG. 2 is a front elevational view thereof;

FIG. 3 is a top plan view thereof;

FIG. 4 is a side elevational view thereof;

FIG. 5 is a side elevational view shown with the cap removed;

FIG. 6 is a rear elevational view of the device as shown in FIGS. 1-4.

FIG. 1

FIG. 2

FIG. 3

FIG. 4

FIG. 5

FIG. 6
